UNITED STATES PATENT OFFICE.

WILLIAM E. BALDWIN, OF NEW YORK, N. Y.

BOOK.

Application filed November 20, 1924. Serial No. 751,027.

To all whom it may concern:

Be it known that I, WILLIAM E. BALDWIN, a citizen of the United States, and resident of the borough of Manhattan, in the city, 5 county, and State of New York, have invented certain new and useful Improvements in Books, of which the following is a specification.

My invention relates to books of the type 10 having a permanent body of leaves bound between covers and adapted to have a supplement in the form of a pamphlet, note book, or the like, inserted between one of the cover members of the book and the body of permanent leaves.

One of the objects of the invention is to provide a book of this type of sturdy, durable construction which will present a neat, trim appearance, with all of its edges true, 20 and without slack in the binding when the supplement is removed.

Another object of the invention is the provision of a book of this type having a structure adhering as nearly as possible to that 25 of a book of standard form and adapted to be manufactured by the standard methods of book-binding.

In the drawings:

Figure 1 is a perspective view of the book 30 with one of the cover members opened and the supplement removed;

Fig. 2 a similar view of a portion of the book upon a larger scale;

Fig. 3 a view similar to Fig. 1 showing 35 the supplement in position;

Fig. 4 a detail perspective view of the supplement; and

Fig. 5 a fragmentary end view partly in 40 section of the book with the supplement in place.

Referring to the parts by numerals, 1 and 45 2 designate the cover members of the book and 3 designates the back. A body of leaves 4 are permanently bound to the back in the usual manner. The back is made wider than the thickness of the body of leaves in order to provide a space between the said body and the cover member 2 to receive a removable supplement 5. Extending forwardly for a 50 slight distance from the back of the book in the space between the body of leaves and the cover member 2 is an abutment stub 6. This stub is formed of a body of stub leaves 7 and a fabric binding strip 8. In the manufacture of the book a sufficient number of 55 leaves to completely fill the space between

the covers are bound to the back of the book in the usual manner. A desired number of the leaves adjacent the cover member 2 are then severed on a line extending parallel to the back and a short distance therefrom. The severed portions of the leaves are next removed leaving the stub leaves. The stub leaves are therefore bound to the back along with the main or full-size leaves, and by the 60 same binding operation.

The binding 8 is in the form of a strip of fabric which is folded over and completely covers the forward edges of the stub leaves and the inner and outer faces of the body of 65 said leaves. The strip 8 extends to the back of the book at either side of the stub 6, is folded and lapped upon itself as at 9 and 10 and is secured to the adjacent main leaf as at 11 and to the inner side of the cover 70 member 2 as at 12. Throughout its whole area of contact therewith the fabric strip is pasted to the stub 6, the cover 2 and the body of leaves 4. The stub leaves are thus 75 bound together to form a body and their forward edges are protected by the fabric.

The cover 2 has a layer of material 13 secured thereto at the forward and side edges of the cover. This layer 13 extends rearwardly to a point adjacent the forward 80 edge of the abutment stub and forms with the inner face of the cover 2 a pocket which opens toward the stub. The supplement 5 is formed of a body of leaves bound to a cover 14 preferably of stiffer material than the 85 leaves. In placing the supplement within the book one of the members of its cover 14 is inserted within the said pocket upon the cover member 2, as shown in Fig. 3, and the back of the supplement is pressed against 90 the end of the abutment stub 6. The walls of the pocket fit the inserted cover member of the supplement snugly and serve to frictionally hold it and retain the supplement in place within the book with its back or folded 95 edge abutting the stub and its edges true with the edges of the main leaves of the book. It will be understood that the abutment stub may be formed in other ways and secured within the book in a different manner from that shown and described.

The leaves of the supplement are slightly narrower than the leaves of the main body of the book but they are substantially of the same length so that when the supplement is in place the edges of the leaves thereof are flush with the free edges of the leaves 100 105 110

of the main body of the book. This is very desirable because the book with the supplement inserted has the appearance and finish of a single complete book and it is not obvious that the book contains a removable supplement. The entrance to the pocket is arranged close to the flexible connection between the pocket-carrying cover and the back, so that when the supplement is secured 5 in place and the covers are closed it will be practically impossible for the supplement to shift and get out of line with the main body of the leaves even though the book be roughly handled.

10 The edges of the leaves in the stub are exposed at the ends of the stub and these exposed edges are flush with the corresponding exposed edges of the leaves of the main body of the book. The advantage of this is that 15 when the supplement is in place and the book covers are closed the entire book has the appearance of a completely bound book without a supplement. The break in the leaves between the ends of the stub leaves 20 and the inner bound edge of the supplement is not noticeable due to the fact that the edges of the stub leaves are exposed and that the stub leaves are bound as a part of the bound book and that their exposed edges 25 are trimmed flush with the exposed edges of the leaves of the main body of the book. The supplement is preferably substantially as thick as the abutment so that when a supplement is in place the book covers will 30 be substantially parallel with each other.

35 From the foregoing it will be seen that I have provided a book that is extremely simple and requires only very slight additional work in its manufacture over the manufacture 40 of a book of standard form. The book presents a neat, clean-cut appearance either with or without the supplement inserted. When the supplement is inserted there is no bulging of the cover members or back of 45 the book and when it is removed there is no slack in the binding. The abutment stub in combination with the pocket serves to ac-

curately position the supplement, and the stub and its binding serve to firmly reinforce the back and maintain its shape. When the book is closed the back will be maintained rigidly in its proper form regardless of whether or not the supplement is inserted, and the stiff back structure will hold all of the edges of the book true. 50

What I claim is:

In a book the combination of a back, a pair of covers flexibly connected to the said back, a compact body of leaves permanently secured to the said back and completely and solidly filling the back from cover to cover said leaves being in contact with each other and rigidly supporting the back throughout its entire area and rendering the back rigid to resist lateral compression, some of said leaves forming the main body of the book and some of said leaves being short and extending a short distance outwardly from their point of attachment to the back to form a short abutment stub extending the full length of the back adjacent one cover member and adapted to contact with said cover member along its flexible connection with the back, the main body of the book and the abutment stub maintaining the back of the book at a fixed width the edges of the leaves at the ends of the stub being exposed and cut flush with the edges of the leaves of the main body of the book, a permanent fabric binding covering and securing together the forward edges of the stub leaves, a supplement having a body of leaves smaller than the leaves of the main body of the book and having a cover member said supplement having a bound edge in contact with the free inner edge of the abutment stub and the free edges of its leaves flush with the edges of the leaves of the main body of the book, and means for removably securing the supplement cover to the book cover. 60

85 In testimony whereof I hereunto affix my signature.

90 WILLIAM E. BALDWIN.
